HEAT TRANSFER SYSTEM

Cecil E. Stiner, Drexel Hill, Pa., assignor to Alcorn Combustion Company, Philadelphia, Pa., a corporation of Delaware

Application February 24, 1939, Serial No. 258,165

4 Claims. (Cl. 196—110)

My invention relates to heat transfer systems, particularly those utilized for the elevation of petroleum and its derivatives to distillation and cracking temperatures.

5 In accordance with U. S. Patent #2,129,589, granted to F. H. Praeger on September 6, 1938, combustion chambers or muffles are provided for the partial completion of combustion of fuel and for directing burning gases laterally across a 10 fire chamber and above and in avoidance of convective transfer with floor tubes disposed therebeneath. As shown in said patent, the muffles rest upon refractory brickwork which is supported from the floor of the combustion chamber. 15 It has also been proposed to mount the combustion chambers externally of the fire chamber with the discharge-ends thereof directly adjacent an inner wall of the fire chamber. In the latter case, and partly to take care of the large 20 heat-release, air in excess of that required for combustion flows over the walls of the combustion chambers. Nevertheless, the temperature of those walls may become excessively high since the only cooling provided therefor is by the said 25 flow of air; and it is impracticable to supply that air in amount adequate substantially to reduce the wall temperature. The maintenance due to deterioration of those walls is high even though expensive refractories be utilized.

30 It has also been proposed to construct muffles of metal which are supported upon refractory brickwork. In those cases it has been difficult to prevent burning or melting of the metal, particularly where the muffle joins or rests upon its 35 support, because at that point heat is not removed at high rate and the temperature rises accordingly.

These prior constructions, even though reasonably satisfactory, leave something to be desired 40 in the more efficient utilization of the combustion space within the fire chamber, and in the length of the useful life of the muffles or combustion chambers.

In accord with my invention, the combustion 45 chambers, tubular in form, are constructed of a self-supporting refractory, such as metal, which is as great a degree as possible is chemically inert at incandescence to the burning combustion gases; and each tubular chamber is provided 50 with means at the firing end for the support of the entire chamber from a point adjacent a side wall. Accordingly, without increase in size of the heater, a greater heater capacity is obtained by the addition of floor tubes below the combustion chambers and in the unobstructed space

previously occupied by the supporting brickwork. Floor tubes in this position increase the fluid-conducting heat-absorption areas, which, because of the high rate of heat transfer thereto, materially increases the permissible throughput for a given outlet temperature without increasing the fire-box temperature; and the addition of two or three floor tubes directly beneath the combustion chamber will serve materially to reduce the fire-box temperature where the same throughput and outlet temperature is desired. 5 Heat is radiated from the walls of the combustion chambers at a rate to prevent burning or melting of the walls thereof; and from every unit area thereof to heat-absorption surface to prevent overheating of any part of the combustion chambers; moreover, the supports for the muffles or combustion chambers are entirely outside the zone of combustion and are not subject to burning or melting temperatures.

20 For a more complete understanding of my invention, reference should now be had to the drawings, in which:

Fig. 1 is a side elevation, partly in section, of a heater embodying my invention;

Fig. 2 is a fragmentary sectional view taken on the line 2—2 of Fig. 1.

Fig. 3 is a fractional end view of one of the combustion chambers, with the burner structure omitted.

Fig. 4 is a side-elevation, partly in section, of a heater embodying my invention in a modified form; and

Fig. 5 diagrammatically illustrates a different sequence of flow of fluid through the tubes of Fig. 4.

Referring to the drawing, I have shown my invention in one form as applied to an oil or petroleum heater 10, having a roof 11, a front wall 12, a rear wall 13, and a floor 14, respectively formed 40 of firebrick or equivalent, which define a fire chamber 15. The rear wall 13 in conjunction with a sloping portion 11a of the roof forms a convection section comprising a plurality of oil-conducting, heat-absorbing tubes 16, the outlet 45 from the convection section being by way of the duct or passage 17 to stack (not shown). A bank of roof tubes 18 are suitably supported from the roof of the heater, and/or from roof-supporting structure (not shown). A bank of floor tubes 19 extends, Fig. 2, between the opposite end-walls 20 and 21, and may rest upon intervening supports, where the length of the tubes is sufficiently great. Headers interconnecting the floor tubes for serial or parallel flow of fluid have been 50 55

omitted for the sake of clarity, the flow being shown diagrammatically.

Within a plurality of muffles or combustion chambers 22 to 25, fuel, as delivered from burners 5 26 to 29, as gas, or oil, or both, is burned. The combustion of the fuel is partially completed within the muffles, which guide and direct the gases discharged therefrom, the guiding and directional effects being of a character to maintain 10 the currents of gases above, over, and across the floor tubes 19. As explained in the aforesaid Praeger patent #2,129,589, the floor tubes 19 are disposed below and without the currents of gases and absorb heat substantially solely by radiation; 15 thereby providing for higher average heat inputs to the several banks without excessive rates of heat absorption anywhere in the fluid-conducting tubes. Some of the roof tubes 18, particularly those near the convection tubes 16, receive heat 20 by radiation and convection, while the mode of heat-transfer to the tubes 16 is largely by convection.

The combustion chambers or muffles 22 to 25 may be of identical construction. More particularly, the muffle 25 is formed of a refractory metal, as nearly as possible chemically inert and highly resistant to deterioration at incandescence to combustion gases and at incandescence having sufficient strength for the entire support thereof 30 from one end thereof. While each muffle may be constructed of an alloy comprising iron, nickel, and chromium in various proportions, I prefer to utilize a strong heat-resistant alloy steel including nickel 12%, chromium 30%, and carbon .35%, 35 maximum, though other equally or greater heat-resistant alloys or materials may be utilized; and preferably those having sufficient strength at operating temperature to be supported from one end thereof.

40 As illustrated, the muffle 25, of tubular form, is provided with a flange 30 through which extend a plurality of bolts 31, which bolts pass through the flanges 32a of a collar 32 and through steel sheathing 33 provided for the front wall 12 of the heater. The muffles need not be of circular cross-section, though in the preferred form of my invention they are all illustrated as circular. Adjacent the open end of each muffle and within collar 32 a refractory insert 37 may be secured, as 50 by screws, to form a Venturi throat which assists in the introduction of the amount of air required for the combustion of fuel introduced by the burner 26. The arrangement is such that the major burning of the fuel occurs at a point to 55 the right of insert 37 (as viewed in Fig. 1) and beyond the flange 30, wherefore the supporting elements are removed from the zone of combustion having the highest temperature; and all portions of the muffles forming the combustion zone 60 comprise radiating surfaces. My invention is further characterized by locating the supporting ends of the muffles in a zone not subject to high, damaging temperatures, and for the remaining 65 portions of the muffles there is adequate radiation of heat to the roof and floor tubes to prevent burning or melting or undue short life of the metal muffles. Where additional supports are desired they may take the form of simple rods extending from the outer end of each muffle to the 70 floor or tube therebeneath, or to the front wall. The rate of firing is under the control of the respective burner-control valves 39 to 42. Preferably a passage formed by a metallic wall 44 is 75 provided for the air supply to the muffles. In

some instances it is desirable to preheat the air prior to admission to the muffles.

In accord with my invention, the metallic muffles operated at incandescence and forming radiant sources of heat serve to transmit heat 5 solely by radiation directly to the roof tubes 13 and the floor tubes 19 which are within radiant view thereof. The aforesaid alloy is characterized by the large amount of heat radiated therefrom, materially more than from silicon carbide 10 and the like. For example, the metallic tube has approximately one-third greater heat conductivity than silicon carbide and is not nearly as great in thickness.

After long continued operation, of a year or 15 more duration, the metal forming the muffles, which may be relatively thin, as of the order of $\frac{1}{8}$ ", may wear away to some extent as by erosion caused by hard particles contained in the fuel, by oxidation, acid attack, or by a combination of 20 all of these causes. The wall thickness of each muffle may finally become so thin as to permit the appearance of openings therein. Nevertheless, the muffles may be operated for some time after it appears that replacement will soon be 25 necessary. The directional effect upon the gases, while lessened somewhat, is generally sufficient for the continuance of a particular run and is not at all comparable with those cases where refractory material fails and drops into the interior 30 of the muffle forming deflectors which may cause the gases to move directly towards the heat absorption structure. Replacement of the muffles is exceedingly easy since that may be done by 35 merely removing the nuts from the bolts 31 and by inserting new muffles in the place of those which have served their usefulness. While other muffle supporting means may be utilized, which provide for the removal of the muffles from without the fire chamber, as by extending the muffles through 40 the front wall, Fig. 4, and mounting the Venturi block or insert therein, and while for additional muffle supports single rods may extend from the outermost end of each muffle to the floor therebeneath, or upwardly to the front wall, I have illustrated and described the preferred form of my 45 invention.

Referring to Fig. 4, I have shown a modified form of my invention as applied to a heater 50 50 provided with a plurality of muffles 51, spaced laterally along a front wall 52 of the heater, each muffle being provided with a Venturi burner-block 53 and fuel-delivering nozzle 54. Each of muffles 51 is supported from the front wall 52 as 55 by bolts (shown in Figs. 1 to 3). The major part of each muffle extends outwardly over a plurality of floor tubes 55, and serves to direct currents of burning combustion gases over, above, and in avoidance of convective transfer to the floor tubes 60 55 therebeneath. Oil entering at 56 passes through floor tubes 55, leaving the heater by way of line 60.

A second stream of oil enters at 61 into a lower convection bank 62, through an upper convection 65 bank 51, and by way of transfer line 63 enters a plurality of roof tubes 64, leaving the heater by way of line 65. Where two streams of oil are heated within the same furnace, it is frequently desirable to elevate the separate streams of oil, 70 which may be in liquid or vapor phase, to different discharge temperatures.

To provide independent control of the discharge temperatures, I provide a plurality of metallic muffles 66 disposed laterally across the con- 75

vection section. Each muffle 66 extends through the end wall 67 and through the bridge wall 58. Fuel is supplied to each muffle through a burner-nozzle 68, substantial combustion of the fuel occurring within the muffle, and the still-burning gases being discharged outwardly from the bridge wall 58. The combustion of fuel elevates the muffle walls to incandescence, each muffle giving up substantial quantities of heat by direct radiation to the convection tubes 57 and 62. Heat is absorbed by the roof and floor tubes from the gases discharged from the muffles 66, to some extent still-burning. These gases, under the influence of the draft imparted by the stack (not shown), rise and also convectively heat some of the roof tubes 64.

By varying the rate at which fuel is burned within muffles 66, the temperature of the stream entering by way of line 61 and leaving by way 20 of line 65 may be controlled. By increasing the rate of fuel consumption, the discharge temperature may be increased. Though the floor tubes 55 also absorb additional heat, due to radiation from the flame from muffles 66, this additional 25 heating may be compensated for by decreasing the rate of fuel supplied to muffles 51; thereby to provide a corresponding decrease in the heat radiated to, and absorbed by, floor tubes 55. By 30 independently adjusting the rates of firing it will be seen that any desired discharge temperature may be maintained on the stream entering at 61 and leaving at 65 while the same discharge temperature is maintained on the stream entering at 56 and leaving at 60. Conversely, the outlet 35 temperature of the stream 56 to 60 may be varied and the outlet temperature of stream 61 to 65 maintained constant; or both outlet temperatures may be simultaneously varied.

As shown in Fig. 5, the tubes 57 are connected 40 directly to roof tubes 64 for the stream entering at 56 and leaving at 65, while the stream entering at 61 may pass directly through the tubes 62, the floor tubes 55, and leave by way of line 60. In this form of my invention an increase 45 in the rate of firing with respect to muffles 66 serves to increase the amount of radiant heat received by tubes 51, as well as to increase the amount of heat received or absorbed by roof tube 64, and additionally to increase the heat absorbed 50 by tubes 57 by convection. As before, an increase in the heat absorbed by tube 62 may be compensated for to some extent by decreasing the rate of fuel consumption within the muffles 51, which primarily determine the heat absorbed by 55 floor tubes 55.

The metallic muffles 66 completely enclose the burning fuel and prevent flame impingement upon the convection tubes 57 and 62, which are ordinarily made of carbon steel, while the tubes 60 55 and 64 are ordinarily made of the more expensive, higher heat-resistant alloys. If desired, the muffles 66 may be secured to the end wall 67 in manner shown in Figs. 1 and 2, and above described.

While I have shown particular embodiments 65 of my invention, it will be understood that I do not limit myself thereto since many modifications may be made and I, therefore, contemplate, by the appended claims, to cover any such modifications as fall within the spirit and scope of my 70 invention.

What I claim is:

1. A furnace comprising a heating chamber traversed by burning gases, heat absorption structure within said chamber comprising a bank of floor tubes, combustion chambers, each comprising a tubular radiating wall of refractory material, means for supporting each combustion chamber from one end of its tubular wall, each of said combustion chambers extending generally horizontally from the supporting means into said heating chamber and over and above several of said floor tubes, an up-standing bridge wall forming with a rear wall a convection section, additional combustion chambers, each comprising a tubular radiating wall of refractory metal extending across said convection section and receiving fuel from without the heater and for discharging the burning gases outwardly away from said bridge wall, and a bank of convection tubes disposed above and below said last-named 20 muffles.

2. Oil-heating apparatus comprising a heating chamber, an up-standing bridge wall forming with a back wall of said fire chamber a convection section, a plurality of combustion chambers 25 disposed laterally across said convection section, each comprising a tubular radiating wall of refractory metal extending from the rear wall through said bridge wall, means for effecting combustion of fuel in each of said combustion 30 chambers, separate banks of convection tubes disposed above and below said combustion chambers, and floor tubes and roof tubes respectively connected to said convection tubes above and below said combustion chambers for the passage 35 therethrough of separate streams of oil.

3. Oil-heating apparatus comprising a heating chamber, an up-standing bridge wall forming with a back wall of said fire chamber a convection section, a plurality of combustion chambers 40 disposed laterally across said convection section, each comprising a tubular radiating wall of refractory metal extending from the rear wall through said bridge wall, means for effecting combustion of fuel in each of said combustion 45 chambers, separate banks of convection tubes disposed above and below said combustion chambers, floor tubes and roof tubes respectively connected to said convection tubes above and below said combustion chambers for the passage 50 therethrough of separate streams of oil, and combustion chambers extending between said roof and floor tubes for burning additional fuel to increase the heat input to said tubes.

4. Oil-heating apparatus comprising a heating 55 chamber, burners for producing combustion of fuel and generation of heat within said chamber, oil-conducting heat-absorbing structure within said chamber, a convection section receiving the products of combustion from said chamber, elongated combustion chambers formed of refractory material extending across said convection section and discharging into said chamber, means for burning fuel within said combustion chambers to heat them to heat-radiating temperature, 60 and oil-conducting heat-absorbing structure disposed on opposite sides of said combustion chambers and receiving radiant heat therefrom and heat by convection transfer from said products of combustion.

CECIL E. STINER.
